UNITED STATES PATENT OFFICE.

JESSE L. JONES, OF EDGEWOOD, PENNSYLVANIA, ASSIGNOR TO WESTINGHOUSE ELECTRIC & MANUFACTURING COMPANY, A CORPORATION OF PENNSYLVANIA.

METHOD OF AND APPARATUS FOR DIE CASTING.

Application filed November 20, 1923. Serial No. 675,831.

My invention relates to pressure casting, more especially to an apparatus for casting metal bodies, such as squirrel cage rotors for dynamo-electric machines in dies or molds under relatively high pressures.

It is among the objects of my invention to provide a device for casting metal bodies under pressure which shall be of simple, durable, mechanical construction and which shall be efficient in the casting of rotors or the like with uniform results and in production quantities.

Pressure casting methods as ordinarily practiced, utilize a die or mold of the shape and contour of the body to be formed, the molds being sometimes adapted to hold a structure which becomes a part of the casting formed therein. The die or mold is provided with a reservoir which contains a molten metal, such as aluminum, copper or the like, which is forced through one or more communicating ports into the matrix of the mold under relatively high pressures.

The cooling of the metal in the mold results in irregularities due to shrinkage and blow-holes, if the pressures utilized are insufficient to counteract the stresses set up in cooling.

I propose to overcome these irregularities in the casting by filling the mold from two or more sources so that the metal forced into the mold from one side will be compressed by the metal subsequently forced from the opposite side a short time later.

In the accompanying drawing constituting a part hereof and in which like reference characters designate like parts, the single figure is a vertical sectional view of a pressure casting device embodying the principles of my invention.

The device comprises a die or mold 1, consisting of a cylindrical shell 2 having an off-set portion 3 and which is mounted on a base 4 in a suitable manner, as by means of a connecting flange 5 which constitutes the base plate of the mold. A cylindrical member 6 is mounted on the top of the mold 1 by a flanged plate 7 which constitutes the clamping member of mold 1.

The members 4 and 6 are provided with cylindrical openings 8 having pistons 9 and 10, respectively, movably mounted therein.

The openings 8 constitute reservoirs in which the molten metal, such as aluminum, copper or the like, is stored and the pis-

tons 9 and 10 are connected up in a suitable manner to be successively operated by mechanical levers or by the usual pressure-actuated devices.

A rotor 12 comprising a plurality of superposed steel laminations having a central opening 13 and a plurality of slots or openings 14, which receive the metal to constitute the rotor bars when the casting is completed, is assembled between the base plate 5 and the clamping plate 7. The plates 5 and 7 are so formed as to provide annular recesses 15 at the ends of the members 12, the metal within which constitutes the end rings of the rotor when cast. The end rings are formed integral with the metal conductors in the slots 14. The mold 1 is provided with a plurality of port-holes 16 which are closed by asbestos, cloth or the like to prevent the molten metal 11 from the flowing into the mold prematurely, before the piston members are actuated.

When the laminated rotor 12 is assembled between the plates of the mold as shown, the bottom piston 9 is actuated to force the molten metal from the lower reservoir into the spaces 14 and 15 and form the lower end ring and a portion of the conductor bars, the amount of metal in the reservoir being limited so as to only partially form the casting. A short interval after the forming of the lower body portion of the casting, the upper piston member 10 is actuated against the metal in the upper reservoir which is forced into the mold under extremely high pressure, before the metal discharged from the lower reservoir is completely set or hardened, thus tending to counteract the effective shrinkage in the bottom casting to prevent the shrinkage of the metal and the formation of blow-holes.

The mold 1 is then removed by actuating it about the pivot pins 17 and the casting is discharged by removing the upper clamping plate 7 which gives access to the casting and the latter is readily removed by unscrewing the clamping bolt 18 and raising the casting out of the matrix 2. A new rotor is then inserted and the operation repeated.

It is evident from the above description of my invention that a pressure casting device as set forth herein provides an efficient means for forming pressure cast bodies of homogeneous structure and with uniform re-

sults and especially bodies of metal having relatively high shrinkage, as the shrinkage resulting from the cooling of the metal is counteracted by the subsequent supply 5 from the second source. My device is especially adapted for casting end rings and conductor bars on squirrel cage rotors for dynamo electric machines as these members are of irregular cross-section, which offers a 10 relatively large cooling surface for the metal.

Although I have described a specific embodiment of my invention, it will be obvious to those skilled in the art that the 15 general design features may be varied in proportions and mechanical fittings to adapt them for the casting of various sized rotors and bodies of other shapes than herein illustrated without departing from the spirit of 20 my invention.

I claim as my invention:—

1. A method of casting bodies under pressure which comprises forming such bodies by casting molten metal under pressure from 25 a plurality of independent sources successively into a single mold.

2. A method of casting bodies under pressure which comprises forming such bodies by casting a portion of the body from a 30 reservoir containing a limited amount of metal and completing the body from a second reservoir, the metal being forced into the mold under pressure from both reservoirs.

3. A method of casting bodies under pressure which comprises forming such bodies by casting a portion of the body under pressure from a reservoir containing a limited amount of metal and completing the body 35 with molten metal cast under pressure from another reservoir after the first named reservoir has been discharged.

4. A method of casting bodies under pressure which comprises forming such bodies 40 by casting a portion of the body under pressure from a reservoir containing a limited

amount of metal and completing the body with molten metal cast under pressure from another reservoir at a slight interval after the first reservoir is discharged. 50

5. A pressure casting device comprising a mold, a plurality of reservoirs for holding a supply of molten metal, communicating means for said mold and reservoirs and means for discharging said reservoirs at successive intervals. 55

6. A pressure casting device comprising a mold, a plurality of reservoirs for holding a supply of molten metal, communicating means for said mold and reservoirs and 60 means for independently discharging said reservoirs at successive intervals.

7. A pressure casting device comprising a mold adapted to receive a frame in or about which a body is to be cast, a plurality of 65 reservoirs associated with said mold, a plurality of communicating ports in said mold and reservoirs and pressure actuating means for discharging the reservoirs through said ports. 70

8. A pressure casting device comprising a mold adapted to receive a frame in or about which a body is to be cast, a plurality of reservoirs associated with said mold, a plurality of communicating ports in said mold 75 and reservoirs and pressure actuating means for discharging the reservoirs through said ports, said means comprising a plurality of fluid pressure actuated pistons.

9. A pressure casting device comprising a 80 mold, means for clamping a body therein in such a manner as to provide a space which constitutes the matrix in which a casting is formed, a reservoir for the top and the bottom of said mold having communicating 85 ports therebetween and pressure actuating means for discharging the said reservoirs successively.

In testimony whereof, I have hereunto 90 subscribed my name this 14th day of November, 1923.

JESSE L. JONES.
